Primary Examiner — Angela J Lee(74) *Attorney, Agent, or Firm* — Weaver Austin Vileneuve & Sampson LLP**(57) CLAIM**

The ornamental design for a luminaire, as shown and described.

DESCRIPTION

FIG. 1 shows a lower perspective view of a first embodiment of the design;

FIG. 2 shows an upper perspective view of the embodiment of FIG. 1;

FIG. 3 shows a bottom plan view of the embodiment of FIG. 1;

FIG. 4 shows a side view of the embodiment of FIG. 1;

FIG. 5 shows an environment of the embodiment of FIG. 1, which is not part of the design;

FIG. 6 shows a lower perspective view of a second embodiment of the design;

FIG. 7 shows a bottom plan view of the embodiment of FIG. 6; and,

FIG. 8 shows a side view of the embodiment of FIG. 6.

FIGS. 1-2 and 4-8 show elements of the luminaire in broken lines which form no part of the claimed design. The jagged line in the figures is included to show a luminaire as broken away. The portion not shown in the figures forms no part of the claimed design.
